UNITED STATES PATENT OFFICE.

ADOLPHE BEAUDINET, OF BRUSSELS, BELGIUM.

APPARATUS FOR CHECKING OR RECORDING THE PERFORMANCE OR RUNNING OF MACHINES OR VEHICLES.

1,414,324.

Specification of Letters Patent. Patented Apr. 25, 1922.

Application filed October 19, 1912. Serial No. 726,784.

(GRANTED UNDER THE PROVISIONS OF THE ACT OF MARCH 3, 1921, 41 STAT. L., 1313.)

To all whom it may concern:

Be it known that I, ADOLPHE BEAUDINET, a subject of the King of Belgium, residing at 1 Rue des Oeillets, Brussels, Belgium, have invented new and useful Improvements in an Apparatus for Checking or Recording the Performance or Running of Machines or Vehicles.

This invention relates to a recording apparatus for checking or recording the operation of mechanism whether the performance is carried out constantly or intermittently, whether the mechanism runs in one direction or the other, or whether the running takes place under load or otherwise.

The principal object of the invention is to improve and simplify the general construction of devices of this character.

A second object of the invention is to provide an apparatus wherein, by improved means, the characteristics of all movements of the mechanism whose performance is to be recorded are automatically shown on a diagram.

A third object of the invention is to provide means of this character which may have the record either visible or concealed in a casing.

The apparatus is substantially formed by the combination of two common mechanical movements; of a clock work mechanism measuring the time, and a second mechanism actuated from the machine whose record is to be kept and indicating the various features or characteristics to be recorded. This record may be received either on a continuous band or strip or on disks graduated in a desired manner.

The invention further consists in general of certain novel details of construction and combination of parts hereinafter fully described, illustrated in the accompanying drawings, and specifically claimed.

In the accompanying drawings, like characters of reference indicate like parts in the several views, and

Fig. 1 is a plan view showing an apparatus of the class described wherein the record is inscribed upon a suitable disk, certain portions of the apparatus being broken away to better show the construction.

Fig. 2 is a detail section on the line 2—2 of Fig. 1.

Fig. 3 is a transverse section on the line 3—3 of Fig. 1.

Fig. 4 is a partial detail elevation of a modification wherein the record is kept on a continuous band or cylinder used in place of the disk.

Fig. 5 is a view, partly broken away, of the band, whereon such record has been inscribed.

Fig. 6 is a diagrammatical view showing an arrangement for using a band adapted to record the operation of the machine for a number of days.

Fig. 7 is a face view of the type of band used in connection with the apparatus shown in Fig. 6.

Fig. 8 is a view showing a form of construction wherein the casing is provided with a safety device to prevent tampering with the record, the cover, the disk, and the tracing arm being removed to better show the interior.

Fig. 9 is a detail section on the line 9—9 of Fig. 8.

Fig. 10 is a view similar to Fig. 8 but showing all the parts in position and the device provided with a resilient suspension.

Fig. 11 is a front view of the device disclosed in Fig. 10.

In the form of the construction shown in Fig. 1 there is provided a clock work mechanism indicated in general at *a* and having an arbor whereon is formed a worm *b* engaging a worm wheel *d* carried by a circular plate *c* pivotally mounted on a stud, the head of which is shown at *c'*. The gear ratio of the clock work mechanism, worm and worm wheel is so arranged as to rotate the disk or plate *c* once in a predetermined number of hours, for instance once every 24 hours.

In order to trace a diagram on a suitable disk *g* carried on the plate *c* there is provided a tracing member or arm *f* having a reciprocating movement.

In order to move the arm *f* there is provided a flexible rotary shaft *i* which is driven by the mechanism whose movement is to be recorded. This shaft is connected with a shaft *i'* mounted in bearings *i''* fixed upon a suitable plate *p* which is in itself movable as will be hereinafter explained, 105 On the shaft *i'* is a worm *i''* which meshes

with a worm wheel k journalled on a pin k' fixed to the plate p . On the worm wheel k is fixed an eccentric pin l which engages in a transverse slot m of a link n . This link n has one end mounted in a suitable guide way as formed on the plate p so that when the worm wheel revolves the link will be reciprocated. On the link n is fixed a leaf spring z carrying a stylus or tracing member f the lower end of which bears against the disk g when the latter is in position. Thus the reciprocating movement of the stylus traces a zig zag line on the disk g as long as the shaft i is rotating under the influence of the mechanism whose movement is to be recorded.

The plate p is arranged itself to reciprocate in a guide way t formed on a fixed plate t' suitably supported by a casing of the apparatus, or forming one side of said casing. Projecting from the plate p is a pin q which engages in the helicoidal groove r of a cylinder s carried by a shaft s' , this shaft being suitably connected in any desired manner, not deemed necessary here to be shown with the starting switch or lever of the mechanism whose note is to be recorded.

In the modified form of apparatus as shown in the Fig. 4 the arbor h of Fig. 1 is replaced by an arbor h' whereon is fixed a pinion b' which meshes with a gear d' carried by a cylinder c' whereon is fitted an endless band g' . In this modified form the cylinder is supported on a suitable shaft c^3 corresponding to the support for the disk c . Further the plate t' is arranged parallel to the axis of the cylinder c' instead of perpendicular thereto as in the form shown in Fig. 1. Otherwise the apparatus is the same in construction.

In each of these forms provision may be made for recording the starting or stopping of one phase of the operation of the mechanism and to this end the spring z is provided with a slot z' arranged centrally of the spring and through which a suitable punch or stamp such as is indicated in end view at z may be inserted to make a distinct mark on the disk.

In Fig. 6 there is disclosed a modified form wherein there is employed a strip or band g^2 in place of the endless band g' , the band being wound on a roller or spool u from off a similar roller or spool u' by suitable gearing of well known character connected to the gearing driving the cylinder c^2 but not deemed necessary here to be shown as the same is common in the art. In this form it is preferable to hold the strip g^2 in proper position by means of rollers v' . In the form of construction shown in Figs. 8 to 11 provision is made against tampering with the record as will be presently understood. In this form of the device there is provided a suitable clock work mechanism

indicated in general at 9. On one arbor 5 of this mechanism there is mounted a plate 6 arranged to receive a record disk 31 and provided with a sleeve 67 and whereon the disk is held by means of a washer 7 and nut 8. In the clock work mechanism 9 is included a main spring 11 which is connected to a suitable arbor 13 projecting through an opening in the casing 12 which surrounds the entire apparatus. 75

Within the casing 12 is fixed a plate 10 corresponding to the plate t' of Fig. 1 and having a vertical sleeve 14 formed therein. In this sleeve 14 rotates the sleeve 67 above referred to. On the sleeve 14 is mounted a worm wheel 16 provided with an eccentric hub 15. This worm wheel 16 is driven by means of a worm 18 formed on a shaft 18' which is journalled in suitable bearings 19 carried by the plate 10. This shaft 18' is 85 driven by a flexible shaft 20 from the machinery or mechanism whose motion is to be recorded.

The eccentric hub 15 engages in a slot 22 formed on a plate 23 which is slidably mounted between the guides 24 of a second plate 25 which is itself slidably mounted between guides 26 fixed to the plate 10. Fixed to the plate 25 is a bracket 27 whereon is fixed one end of a leaf spring 28 carrying the stylus 29 (Fig. 10). A plate 30 is also fixed to the plate 27 with its free end spaced from the free end of the plate 27 so that the plate 30 forms a limit stop for the movement of the spring arm 28. 90 95

In order to displace the plate 25 in the guides 26 there is provided on the sleeve 14 a lever 32 having a fork 33 at one end which engages a pin 34 carried by the plate 25 so that as the lever oscillates the plate 25 is 105 caused to move in the slide 26. The other end of this lever is provided with spaced eyes 37 wherein is mounted a pivot 36 through which passes a rod 35 provided with spaced collars 40 and 41, the collar 40 being screwed 110 on the rod as shown. Between these collars and the pivot 36 are coil springs 38 and 39 and by means of the nut or collar 40 the tension of these springs may be adjusted as desired. The rod 35 passes through a 115 suitable opening in the casing and is connected to an extension 41 movable in a guide block 42 fixed to the casing 12. This extension 41 carries a plate 43 on its end and this plate is provided with a slot 44. On the outside of the casing is fixed a bracket 48 whereon is mounted a stub shaft 47 carrying a revoluble disk 46 which is provided with a pin 45 (Figs. 10 and 11) movable on the slot 44 so that as the disk is rotated the 120 rod 35 is caused to move in one direction or the other. Projecting from the disk 46 is an operating handle 49. Furthermore this disk is provided with a peripheral notch 50 so positioned that when the handle 49 is 125 130

turned to the position shown in dotted lines this notch will lie in alinement with a lug 51 projecting from a cover or shield 52 slideable between guides 53 mounted on the casing 12. The casing 12 is provided with a cover 56 which encloses all of the working parts of the device and fixed in the casing beneath the shield 52 is a boss 55'. Through this boss and the cover 56 extends a locking bolt 55 having a suitable opening arranged to receive the shackle 54' of a padlock 54 when the locking bolt is in position. Normally this padlock is covered by the shield 52 but when the disk 46 is revolved to proper position the shield may be slid from over the padlock and access be had thereto. It will be obvious that this unlocking of the device can only take place when the lever 32 has been moved to a predetermined position and that when said lever is in this position the plate 25 and consequently the stylus 29 will also be in a predetermined position relative to the disk 31.

In order to provide a resilient suspension, as from a board 61, the board and the casing 12 are connected by helicoidal suspension springs 57, 58 and 59 while between this board and casing is a leaf spring 62 so that the device thus forms a shock absorber. The lugs 60 are provided for the connection of the casing 12 with the helicoidal springs above noted.

In the operation of the various forms of the device it will be noted that the disk or band whereon the record is inscribed is preferably divided into three bands or zones indicated respectively at *u*, *v* and *w* (Fig. 1). In all forms of the invention the stylus is moved from one zone to the other by the movement of the plate which is guided in the fixed plate while the stylus is moved back and forth across the respective zone by the movement of the two sliding plates relative to each other. Thus the movement of the shaft *s*' or the corresponding features in the other forms regulate the zone wherein the stylus reciprocates while the flexible shaft controls the reciprocation of the stylus in that zone.

In order to understand fully the operation of the device as shown in Figs. 1 and 4, these figures showing the first two forms let it be supposed that the device is used in connection with a taximeter vehicle and that the diagram traced on the disk or on the band indicates the work done by the vehicle from half past eight in the morning until twenty minutes past three in the afternoon.

The disc and the band are divided into twenty-four sections or sectors numbered from 1 to 24, which represent the twenty-four hours of the day and into three concentric or superposed zones (Figure 1 or Figure 4) respectively, on which the diagram of the

running of the vehicle is automatically 65 traced.

In the zone *y* the diagram records the running of the vehicle when empty, in the zone *v*, it records the stationary periods, and in the zone *w* it records the running of the vehicle when loaded. 70

It is assumed that the shaft of the rotary cylinder *s* of the controlling apparatus carries the shaft on which the signal flag is usually employed in taximeter vehicles is 75 mounted, and which shaft and flag are well known and do not require to be shown.

From this diagram, without further explanation, the running of the vehicles can be immediately determined as follows: 80

The vehicle starts empty at half-past eight and travels in this condition to a place corresponding to the point A on the diagram, the signal flag of the apparatus being of course raised. 85

At A it takes up a passenger. The lowering of the flag then causes the stylus to pass from the zone *u* into the zone *w* (line A—B). The vehicle then travels under load up to o. It stops from C to D, then continues still loaded from D to E where the passenger descends; the conductor again raises his flag and the tracer marks the line E—F. The vehicle travels again empty from F—G, then stops from G—H. At H 95 the vehicle takes up a second passenger, the conductor lowers his flag; the tracer is returned by this movement of the flag into the zone *w* (running under load) tracing the line H to I. At J, the passenger leaves the vehicle, the conductor raises the flag, which produces the line J—K in order to bring the tracer back into the zone *u* (empty running) and so on. 100

At the moment which corresponds with 105 the point O of the diagram the vehicle is rendered stationary by an accident, the passenger remains in the vehicle but the driver half raises the flag of his apparatus which brings the stylus into the intermediate zone 110 *v* which is the zone of accidental stopping or "break down" zone.

The duration of this stoppage is indicated by the short circular line P—O; then the accident having been repaired and the running under load is resumed, the conductor lowers the flag which brings the tracer or stylus into the zone *w* and so on. 115

In the example selected, the ratio of transfer between the driving wheel of the vehicle and the mechanism of the tracer or stylus is selected in such a way that for the distance of one kilometre traversed by the vehicle, the toothed wheel K makes a complete revolution, that is to say the tracer 120 executes a complete reciprocating movement returning to its point of departure. 125

Consequently each line connecting two

apices or successive points of one of the zig zag curves of the diagram corresponds to a distance traversed of half a kilometre; and by multiplying the number of lines between two successive apices of one of the curves by two, the number of kilometres covered is obtained.

If the number of lines thus traced in the same section, for instance in an hourly section of the diagram increases, it is because the speed of travelling is itself increased.

The diagram traced thus indicates the distance traversed by the vehicle during each period of running; it also indicates the speed at any moment in each period. Further according as the diagram is traced in the zone *u* or the zone *w*, the diagram indicates that the vehicle was running empty or loaded, and in addition indicates whether the vehicle was stationary whilst waiting for its passenger, or for any other reason.

If the diagram is traced in the zone *v* it indicates that the vehicle has undergone an accidental stoppage or "break down" and the length of the line traced indicates the duration of this breakdown.

Finally, the diagram indicates the exact hour of commencing, and the end of each period of working and of stoppage.

It is quite evident that the diagram indicates at any moment whether the vehicle is running forward or backward, according to the direction in which the line is traced.

The indications furnished by the diagram are evidently the same if the tracing takes place on a disc or on a band for a single day or a continuous band for several successive days.

If the vehicle is successively driven by different drivers, each of these drivers can mark on the diagram the end of his service.

For this purpose the spring *z* carrying the stylus *f* (Figure 1) is provided with the slot *x*, so that the conductor can insert by hand into this slot a special punch such as *X*. This punch marks on the disc the figure or distinctive number of the driver in question.

In the third form of the device the record disk is divided in a slightly different way. In this instance the recording disc is divided into two concentric annular zones 63, 64, (Figure 10) which are each divided into fourteen sections, each corresponding to the angular displacement of the disc carrying plate 6 during one hour of the running of the clock work movement. These two zones are separated by an annular neutral zone 65.

When the disc with the handle 49 has been brought into the position shown in Figure 1, the stylus 29 is displaced to and fro in the zone 63 or zone of the day's working. When this same disc is turned through 160° and brought into the position shown in Figure 3, the stylus moves in the zone 64 or the zone 65 corresponding to night working. If the

disc in question is simply turned through 90° that is to say brought into such a position that its notch 50 comes beneath the lug 51 provided on the shutter 52 which covers the padlock 54, the stylus moves to the neutral zone 65 and marks on the diagram disc a line indicating that the box has been opened or an attempt has been made to open it with a view to changing the disc or falsifying the diagram. The record line of such an operation is then marked, for instance as at 66 (Figure 10). The stylus has passed rapidly from the zone 64 into the neutral zone 65 and has left in this letter a circular line which indicates the hour at which the box was opened, and the time which elapsed from the opening to the closing of said box.

The reading of the diagram placed on the recording disc and shown in Figure 10 enables the running of the vehicle to be followed minute by minute.

It will be assumed, for the purpose of explaining the working, that the device shown is applied to a taximetre vehicle.

According to the example illustrated in this diagram, the vehicle started from the garage at six o'clock in the afternoon and traveled without stopping up to half-past six, then stopped until 7:15. It resumed running up to 8:20 and then remained stationary up to 9:20.

At this moment it commenced its night service and travelled without stopping up to 10:45 and then stopped up to 11:45. The corresponding diagram is traced in the zone 63 which is that of the day's work in the said zone 64. At 11:45 the conductor of the vehicle wishing, for instance, to falsify the diagram endeavoured to open the box and bring the disc into the intermediate position hereinbefore indicated, as shown in dotted lines in Fig. 1 so that the notch 50 comes beneath the lug 51. This fraudulent action is indicated by the stylus which is brought into the zone 65 and leaves there a circular line 66, which stops at 11:55. The conductor not having been able, for instance, to open the padlock returned the handle disc into its normal position, and let his vehicle stand up to 12:15, at which hour his vehicle resumed running at a somewhat high speed up to 1:15 in the morning, and was then reversed in order to reenter the garage.

The diagram disc continuing to revolve the stylus continues to mark a circular line.

If, as in the case indicated in Fig. 1 the diagram corresponds to one kilometre of running, between two concentric spaces of the line, the speed of travelling can be ascertained at any moment.

The action of the stylus by the movement of the vehicle in each of the two working zones is explained in the following way:

The manipulation of the handle disc 46, in order to bring the stylus into the zone 63, has

for its effect to compress the spring 38 and to expand the spring 39. The action of the spring 38 thus compressed tends to push back the corresponding end of the balancer 5 32, and consequently to bring the sliding plate 25 from the position shown in Figure 8 until it presses elastically against the plate 23, which is actuated to and fro by the eccentric formed on the hub 15 of the toothed 10 wheel 16, which eccentric acts in the slot 22 of the said plate 23.

In the position of this eccentric shown in Figure 8, the plate 23 is at the end of its outward course and is about to commence its 15 return movement. The plate 25, impelled by the action of the compressed spring 36 then follows the return movement of this plate 23 effected by the cam up to the end of the said return movement, the spring 38 progressively expanding. The eccentric 12 20 then again repels the plate 23 and consequently the plate 25 in the outward direction, the effect of which is to again compress the spring 36 and the movement just described is repeated.

It is evident that if the handle disc 46 were brought into the position shown in Figure 10, the spring 39 would be compressed whilst the spring 38 would be expanded. The plate 25 would then bear in 30 the opposite direction against the plate 23 and the spring 39 would act by alternate compressions and expansions, as hereinbefore indicated, in order to maintain the plate 25 35 always pressed against the plate 23, so as to

force this plate 25 to follow the reciprocating movement which the said plate 23 makes under the action of the eccentric on the hub 15.

Having thus described the invention, what 40 is claimed as new, is:—

1. A recording instrument comprising in combination with the recording stylus and the operating means thereof, a casing, a recording means in said casing, a means for 45 locking said casing, a protecting device for said locking means connected to said operating means for the stylus, said connection adapted to allow access to said locking means only at a predetermined position of the 50 stylus operating means, substantially as described.

2. A recording instrument of the character described comprising in combination with the stylus and the operating means 55 thereof, a rotatable disc connected to said operating means and having a slot, a casing, a recording means in said casing, a means for locking said casing, a means for protecting said locking means, a nose on said protecting means, said disc in its central position allowing the passage of said nose for permitting access to said locking means, substantially as described.

In testimony whereof I affix my signature 60 in presence of two witnesses.

ADOLPHE BEAUDINET.
